PROCESS FOR MANUFACTURING 104-106 R.O.N. LEADED GASOLINE

Winton W. Hamilton, Pitman, N.J., assignor to Socony
Mobil Oil Company, Inc., a corporation of New York

Filed June 10, 1959, Ser. No. 819,410

2 Claims. (Cl. 208—79)

The present invention relates to the production of gasoline having a leaded octane number of 104-106 and more particularly, to a method of fractionating a C_4 to 450° F. fraction, preferably a C_4 to 380° F. fraction of straight run gasoline, to isomerize the normal C_5 and C_6 paraffinic hydrocarbons, reform the C_7 and higher hydrocarbons, and alkylate the isobutane produced with C_3 and C_4 olefins from other processes to produce a gasoline containing less than 4 to 7 percent normal paraffins and having a leaded octane number (research +3 cc. TEL) of 104-106 or more.

Broadly, the present invention provides for fractionating a C_4 to 450° F. end point fraction, preferably a C_4 to 380° F. end point fraction, of straight run gasoline to take overhead a C_4 and lighter fraction, to take as a side stream a C_5 and C_6 fraction and to take as a bottoms product a C_6+ fraction. The C_5 and C_6 fraction is isomerized to produce a product containing less than 8 percent by volume and preferably less than 4 percent by volume of normal paraffinic hydrocarbons. The C_6+ fraction is reformed to produce a product containing not more than 10 percent by volume and preferably less than 5 percent by volume of normal and isoparaffins. Preferably, the C_3 and C_4 hydrocarbons are separated from the reformer product. The C_4 hydrocarbons go to an alkylation unit where the isobutane is alkylated with light olefins produced by other operations, such as cracking. The normal butane from the alkylation unit is blended into the finished gasoline to provide the required Reid vapor pressure.

Illustrative of the operations whereby gasoline having a leaded octane number of 104-106 can be made from the C_4 to 450° F., preferably 380° F. end point fraction of straight run gasoline is the treatment set forth in a highly diagrammatic manner in the drawing.

The initial feed is a gasoline fraction containing at least C_5 , C_6 and C_7 hydrocarbons and boiling up to 450° F., preferably 380° F. A substantial proportion of such a feed is paraffinic hydrocarbons.

The gasoline fraction, boiling range C_4 to 450° F., preferably C_4 to 380° F., preferably containing not more than innocuous amounts of sulfur, nitrogen, arsenic and the like, flows from a source not shown through conduit 1 to the suction side of pump 2. Pump 2 discharges the gasoline fraction into pipe 3 through which the gasoline fraction flows to fractionator 4. In fractionator 4, the gasoline fraction is separated at least into an overhead comprising C_4 and lighter hydrocarbons, a side stream comprising normal and isomeric C_5 and C_6 hydrocarbons, and a bottoms product comprising C_6 and heavier hydrocarbons. The overhead, C_4 and lighter hydrocarbons, flows from fractionator 4 through pipe 5 to conduit 6. The side stream comprising normal and isomeric C_5 and C_6 hydrocarbons flows from fractionator 4 through pipe 7 to pipe 8. The bottoms product flows from fractionator 4 through pipe 9 to the reforming unit 10.

When the bottoms product contains innocuous amounts of catalyst poisons such as nitrogen and arsenic, and contains not more than about 20 p.p.m. (parts per million) of sulfur, i.e., insufficient sulfur to require the use of highly corrosion-resistant alloy piping and reactor lining, the reforming unit comprises one or more reforming reactors employed in accordance with static bed, moving bed, or fluidized bed technique, reforming catalyst of a char-

2

acter and quantity to provide a reformate the C_8 and heavier hydrocarbons of which have the target leaded octane rating of at least 104, suitable heaters, means for separating C_4 and heavier hydrocarbon from hydrogen and C_3 and lighter hydrocarbons for use as recycle gas, and a recycle gas compressor for returning to the reforming reactor or reactors the aforesaid recycle gas. On the other hand, when the bottoms product contains more than innocuous amounts of sulfur, nitrogen, arsenic and the like provision must be made to reduce the noxious concentrations of these elements to innocuous concentrations. Thus, for example, when the reforming catalyst comprises a metal of the platinum group on an alumina support the bottoms product feed to the reformer unit is treated to remove all but innocuous amounts of these elements usually by hydrogenation of the bottoms product to provide a treated bottoms product containing not more than about 1 p.p.m. of nitrogen and essentially free of arsenic and lead. (Essentially free of arsenic and lead

20 designates concentrations of arsenic and/or lead such that when said treated bottoms is contacted with a bed of reforming catalyst containing 0.35 percent platinum by weight the catalyst is not deactivated within the life of the catalyst, for example two years, as determined by other factors such as the temperature required to produce a reformate having an octane rating of at least 100 (R.+3 cc.), the yield of reformate and the mechanical strength of the catalyst.)

The bottoms product is reformed in reforming unit 10 in the presence of reforming catalyst to produce a reformate having a leaded octane number of at least 104. The C_4 and heavier hydrocarbons of the reformed bottoms product flow from the reforming unit through conduit 11 to fractionator 12. In fractionator 12 the reformed bottoms product is fractionated at least into an overhead comprising C_3 and lighter hydrocarbons, a side stream comprising C_4 and lighter hydrocarbons, and a bottoms comprising C_5 and heavier hydrocarbons.

The overhead, C_3 and lighter hydrocarbons, flows from fractionator 12 through pipe 13 to the refinery fuel main. The side stream comprising C_4 and lighter hydrocarbons flows through conduit 14 to conduit 6. The bottoms of fractionator 12, C_5 and heavier hydrocarbons, flows through conduit 15 to fractionator 16.

In fractionator 16 the C_5 and heavier bottoms of fractionator 12 is separated into an overhead comprising C_5 and C_6 hydrocarbons, a side stream comprising substantially pure C_6 and heavier aromatic hydrocarbons boiling below about 450° F. and preferably boiling below about 380° F., and a bottoms product comprising hydrocarbons boiling above the gasoline range, i.e., above about 380° F. to about 450° F.

The overhead of fractionator 16 flows through pipe 17 to pipe 8. The side stream comprising substantially pure C_6 and heavier aromatic hydrocarbons boiling below about 380° F. to about 450° F. flows through conduit 18 to means for admixing additives such as anti-knock material, anti-icing material, anti-rusting material, etc. and storage and/or distribution.

Returning now to the side stream comprising C_5 and C_6 normal and isomeric hydrocarbons taken from fractionator 4 through pipe 7, it will be observed that the flow sheet provides for mixing the aforesaid side stream, and an isomerizate (obtained as hereinafter described), and the overhead from fractionator 16 in conduit 8. The mixture of side stream, overhead and isomerizate flows through conduit 8 to fractionator 19. In fractionator 19 the mixture of side stream, overhead and isomerizate is separated at least into an overhead comprising mainly iso- C_5 hydrocarbons, a first side stream comprising mainly normal pentane, a second side stream comprising iso- C_5 hydrocarbons and a bottoms product comprising normal

hexane through plus some isohexanes. The overhead comprising iso-C₅ hydrocarbons flows from fractionator 19 through pipe 20. The first side stream comprising normal pentane flows from fractionator 19 through conduit 21. The second side stream comprising iso-C₆ hydrocarbons flows from fractionator 19 through conduit 22. The bottoms product comprising normal hexane flows from fractionator 19 through pipe 23. The iso-C₅ hydrocarbons flow through pipe 20 to conduit 22 where the iso-C₅ hydrocarbons mix with the iso-C₆ hydrocarbons flowing from fractionator 19 through conduit 22. The mixture of iso-C₅ and iso-C₆ hydrocarbons flows through pipe 22 to pipe 18 where the iso-C₅ and iso-C₆ hydrocarbons mix with the side stream of fractionator 16 comprising substantially pure C₆ and heavier hydrocarbons having an end boiling point within the range 380° F. to 450° F. The bottoms product comprising normal hexane plus some isohexanes flows from fractionator 19 through conduit 23 to pipe 21 where the bottoms product mixes with the first side stream comprising normal pentane. The mixed first side stream and bottoms product, now designated isomer feed, flows through conduit 21 to the isomerizing unit 24.

In the isomerizing unit the isomer feed is isomerized in the presence of a suitable isomerizing catalyst such as aluminum chloride or a solid isomerizing catalyst such as one of the platinum metal type. The isomerate flows from the isomerizing unit 24 through conduit 25 to pipe 8 where, as stated hereinbefore, the isomerate mixes with the side stream from fractionator 4 flowing through conduit 7 and the overhead from fractionator 16 flowing therefrom through pipe 17.

The C₄ and lighter overhead flowing from fractionator 12 through pipe 14 and the C₄ and lighter overhead flowing from fractionator 4 through pipe 5 mix in conduit 6 and flow therethrough to fractionator 26. In fractionator 26 at least an overhead comprising C₃ and lighter hydrocarbons and a bottoms product comprising C₄ hydrocarbon are separated. The overhead comprising C₃ and lighter hydrocarbons flows from fractionator 26 through conduit 27 to the refinery fuel main. The C₄ is taken through conduit 28 to alkylation unit 30. Part or all of the normal butane from the alkylation unit flows through pipe 29 to means for mixing the normal butane with the blend of fractionator 16 side stream flowing through conduit 18 in admixture with the iso-C₅ and iso-C₆ hydrocarbons flowing to conduit 18 through pipe 22 and the alkylate flowing from alkylation unit 30 through conduit 34 (as described hereinafter) to provide the blend having a leaded octane rating of at least about 104 to about 106 or more.

In alkylation unit 30 the isobutane is alkylated with olefins obtained from any suitable source such as a thermal or a catalytic cracking operation. The alkylation unit can be of any suitable type such as, for example, a thermal alkylation unit or an acid alkylation unit employing sulfuric acid, hydrogen fluoride, etc. Thus, the C₄ hydrocarbons flow from fractionator 26 through conduit 28. Olefins from a source not shown flow through pipe 31 to the suction side of pump 32. Pump 32 discharges the olefins into conduit 33 through which the olefins flow to the alkylation unit 30. The alkylate flows from alkylation unit 30 through pipe 34 to pipe 18 where it mixes with the substantially pure aromatic C₆ and heavier hydrocarbons, the iso-C₅ and iso-C₆ hydrocarbons and the normal butane to provide a gasoline blend having the target Reid vapor pressure and a leaded octane rating of at least 104-106.

In the reforming unit the fractionator bottoms or the decontaminated fractionator bottoms are reformed in the presence of an aromatization type catalyst under a severity of conditions of temperature, pressure, hydrogen to bottoms ratio and space velocity to insure conversion of substantially all of the C₆+ hydrocarbons to aromatics. A suitable aromatizing catalyst of the plati-

num type comprises about 0.3 to about 1.0 percent, by weight, platinum, on a support such as alumina or alumina and silica. Suitable aromatizing conditions to convert substantially all of the C₆+ hydrocarbons to aromatics employing a platinum-type catalyst are a temperature within the range about 850° F. to about 1000° F., a pressure within the range about 200 to about 600 p.s.i.g., a hydrogen to bottoms mol ratio of about 4 to 20 and a liquid space velocity of about 0.2 to about 2.0 volume of bottoms per volume of catalyst per hour (v./v./hr.). When employing an aromatizing reforming catalyst comprising the oxide of one or more metals of group VI of the periodic table on alumina as a support, e.g., 18 to 20 weight percent chromium oxide on alumina, the reaction conditions to convert substantially all of the hydrocarbons of the C₆+ fraction to aromatic hydrocarbons are a temperature within the range of about 900° F. to about 1100° F., a pressure within the range of about 100 to about 500 p.s.i.g., a space velocity of about 0.2 to about 1.5 v./hr./v., and a hydrogen to naphtha mol ratio of about 2 to about 10.

When the feed to fractionator 4 has an end point of about 380° F. to 390° F. the side stream in fractionator 16 is substantially pure aromatic hydrocarbons boiling below about 430° F. and is the aromatic fraction of the gasoline having a leaded octane number of 104-106. This side stream product has a leaded octane number of about 114. In this case, there is no bottoms product from fractionator 16. However, when the feed to fractionator 4 has an end point substantially above 380° F. to 390° F. say 400° F. or higher, it is necessary to separate the pure aromatic hydrocarbons boiling in the gasoline range from hydrocarbons boiling above the gasoline range. Such a situation is illustrated in the drawing. Thus, when the feed to fractionator 4 has an end point substantially above 390° F. a substantially pure aromatic hydrocarbon fraction comprising C₆ and C₆+ aromatic hydrocarbons is taken as a side stream through pipe 18 to blending to produce with the alkylate, the isomerized C₅ and C₆ hydrocarbons, and the butanes necessary to produce the required volatility and Reid vapor pressure a gasoline having a leaded octane number of 104-106 or more (research +3 cc. TEL). The higher boiling aromatic hydrocarbons, i.e., boiling above about 430° F., are taken as a bottoms product from fractionator 16 through pipe 40 to storage for use as such, for dealkylation or the like.

It is to be noted that the ultimate product from the isomerization unit contains less than 8 percent and preferably less than 4 percent by volume normal paraffins. The ultimate product from the reforming unit (pipe 18) contains not more than ten percent and preferably less than 5 percent, by volume, of paraffins of any type including isoparaffins. The ultimate product before pressuring with normal butane comprises about 4 to about 7 percent by volume of normal paraffins, about 30 to about 40 percent by volume of isoparaffins, about 50 to about 60 percent by volume aromatics and has a leaded octane number of 104-106 or more (research +3 cc. TEL).

I claim:

1. A method of producing gasoline having a leaded octane number of at least 104-106 (research +3 cc. TEL) which comprises fractionating a C₄ and heavier fraction or naphtha having an end boiling point not greater than 450° F. to provide a first fraction comprising C₄ and lighter hydrocarbons, a second fraction comprising C₅ to C₈ hydrocarbons, and a third fraction comprising hydrocarbons heavier than C₈ hydrocarbons, reforming the aforesaid third fraction in the presence of hydrogen and an aromatizing reforming catalyst under reforming conditions of temperature, pressure, and space velocity to convert substantially all of the hydrocarbons in the aforesaid third fraction to aromatic hydrocarbons and C₈ and lighter paraffinic hydrocarbons to obtain a

reformer effluent comprising hydrogen and C₁ and heavier hydrocarbons, separating the aforesaid reformer effluent into recycle gas comprising hydrogen and C₁ and C₂ hydrocarbons, a fourth fraction comprising C₃ and lighter hydrocarbons, a fifth fraction comprising C₄ and lighter hydrocarbons, a sixth fraction comprising C₅ and C₆ hydrocarbons, a seventh fraction comprising substantially pure aromatic hydrocarbons containing not more than 10 percent by volume of paraffins and having an end boiling point of about 380° to 430° F., and an eighth fraction comprising hydrocarbons boiling above about 380° to 430° F., isomerizing all of the aforesaid C₅ and C₆ fractions comprising the aforesaid second fraction and the aforesaid sixth fraction to produce an ultimate isomerized product (P) containing less than 8 percent by volume of normal paraffins, fractionating the aforesaid first fraction and the aforesaid fifth fraction to obtain a ninth fraction comprising n- and iso-C₄ hydrocarbons, alkylating the iso-C₄ hydrocarbons in the aforesaid ninth fraction with olefins to obtain an alkylate, mixing said alkylate, the aforesaid ultimate isomerized product containing less than 8 percent by volume of normal paraffins, the aforesaid seventh fraction comprising substantially pure aromatics containing not more than 10 percent by

volume of paraffins, and normal C₄ hydrocarbons obtained from the aforesaid alkylation of iso-C₄ hydrocarbons in amount to provide the required volatility and vapor pressure to produce a gasoline blend having a leaded octane number of at least 104 (research +3 cc. TEL).

2. The method of producing gasoline having a leaded octane number of 104 to 106 (research +3 cc. TEL) as set forth and described in claim 1 wherein the C₄ and heavier fraction of naphtha has an end boiling point not greater than about 390° F., and the gasoline blend before pressuring with n-C₄ hydrocarbon comprises about 4 to 7 percent by volume of normal paraffins, about 30 to 40 percent by volume of isoparaffins, and about 50 to 60 percent by volume aromatics.
